UNITED STATES PATENT OFFICE.

PAUL SCHULTES, OF LEICHLINGEN, GERMANY.

TENSIONING DEVICE FOR ROLLER BLINDS.

Application filed June 2, 1927, Serial No. 196,049, and in Germany May 21, 1926.

This invention relates to a spring tension device for self-acting roller blinds, in which the hitherto used pawl which has great disadvantages, is omitted. The new device is 5 so formed that the roller spring can be additionally tensioned when the blind is in use in the simplest manner, without it being necessary to remove the blind and roller.

An embodiment of the invention is shown 10 by way of example in the accompanying drawing.

Figure 1 is an elevation of the whole blind.

Figure 2 is a longitudinal section through 15 the roller.

Figure 3 is a front view of one fixed bearing.

Figure 4 is a corresponding side view.

Figure 5 is an elevation of the coupling device, and

Figure 6 is an elevation of the other bearing.

The blind *a* is guided at its lower end by a rod *b* working in rails *c*. The upper end of the blind is wound on a hollow roller *d*. This 25 hollow roller has at one end and inside, bearing discs by means of which it can rotate on a long shaft *e*. The outer end *f* of this shaft is squared and passes through a corresponding square hole *g* in a coupling disc *h* into the 30 interior of one wall bearing. At the other end the hollow roller is carried in known manner by a pin in a wall bearing *i* having an open slot. A helical spring *m*, which can be tensioned by rotating the parts relative to 35 one another, is secured between a point *k* on the shaft *e* and some fixed point on the outer bearing disc *l*. The coupling disc *h* carries on its rear face two opposite coupling pins *n* which, when the disc *h* is slid along the 40 squared end *f*, enter opposite holes *o* in the disc *l*, whereby the hollow roller *d* is secured fast to the shaft *e*, so that the parts can no longer rotate relatively. On the outer side, the disc *h* has a hollow cylindrical flange 45 formed on it, which engages over a bearing bush *p* secured to the window frame. A pressure spring *r* is arranged within, between the parts *h* and *p* which spring continually presses the disc outwards. The bush *p* has 50 an outwardly projecting rim *t* with two opposite notches *u* (Figure 3) through which corresponding projections *s* (Figure 5) on the cylindrical flange of the disc *h* are passed, and the disc *h* then turned through 90°, when 55 the projections *s* spring into recesses *v* in the rim *t*. In this position the coupling disc is

securely held owing to the spring mounting. This is the normal position when the blind is in use.

The main spring is tensioned in the following manner before the device is mounted in the bearings.

The hollow roller is taken in one hand, and the shaft *e* rotated with the other by the aid of the coupling disc *h* on the squared end *f*. 65 As long as this is rotated the spring is being tensioned. When a sufficient tension is reached, the coupling disc is slid along the squared end *f* until the pins *n* enter the holes *o*, thus coupling the rotatable parts together 70 and preventing the spring from unwinding. The device is now mounted in the bearings, the squared end *f* being first inserted in the bush *p* and the pin at the other end then being inserted through the open slot of the bearing *i*. The coupling disc *h* is then moved to withdraw the pins *n* from the holes *o* and the disc secured by passing it over the bush *p* and 75 rotating it in the above described manner.

If the spring is to be additionally tensioned 80 when the blind is in position, the blind is pulled down, the coupling engaged, the blind wound up by hand and the parts again disengaged. This can be repeated as often as necessary until the desired tension is obtained. 85

What I claim is:—

1. In combination, a shade roller, a shaft loosely mounted in said roller, a roller tensioning spring connected with the shaft and roller, and a coupling member movable axially of the roller and acting in one position to couple the shaft with the roller and in another position to release the roller. 90

2. In combination, a shade roller, a shaft loosely mounted in said roller, a roller tensioning spring connected with the shaft and roller, and a coupling member movable axially of the roller and acting in one position to couple the shaft with the roller and in another position to release the roller, said 95 coupling member being arranged externally of the roller.

3. In combination, a shade roller, a shaft loosely mounted in said roller, a roller tensioning spring connected with the shaft and roller, and a coupling member movable axially of the roller and acting in one position to couple the shaft with the roller and in another position to release the roller, said coupling member being arranged externally 105 of the roller and being slidably mounted on said shaft.

4. In combination, a shade roller, a shaft loosely mounted in said roller, a roller tensioning spring connected with the shaft and roller, and a coupling member movable axially of the roller and acting in one position to couple the shaft with the roller and in another position to release the roller, said shaft being a polygonal end received in said coupling member, and projections on said coupling member engageable with said roller.
5. In combination, a shade roller, a shaft loosely mounted in said roller, a roller tensioning spring connected with the shaft and roller, and a coupling member movable axially of the roller and acting in one position to couple the shaft with the roller and in another position to release the roller, a bearing member for said coupling member and means for maintaining the coupling member in inoperative position with respect to the roller on the bearing member, the last mentioned means including a spring normally tending to displace the coupling member in the direction of the roller.
6. In combination, a shade roller, a shaft loosely mounted in said roller, a roller tensioning spring connected with the shaft and roller, and a coupling member movable axially of the roller and acting in one position to couple the shaft with the roller and in another position to release the roller, a bearing member for said coupling member and means for maintaining the coupling member in inoperative position with respect to the roller on the bearing member.
7. In combination, a shade roller, a shaft loosely mounted in said roller, a roller tensioning spring connected with the shaft and roller, and a coupling member movable axially of the roller and acting in one position to couple the shaft with the roller, a bearing member for said coupling member and means for maintaining the coupling member in inoperative position with respect to the roller on the bearing member, the last mentioned means including a spring normally tending to displace the coupling member in the direction of the roller and coacting flange members carried by the coupling and bearing members.
- In testimony whereof I have signed my name to this specification.
- PAUL SCHULTES.
